US0D1052557S

(12) **United States Design Patent** (10) **Patent No.:** **US D1,052,557 S**
(45) **Date of Patent:** **** Nov. 26, 2024**

(54) **SPEAKER**

(71) Applicant: **ALPS ALPINE CO., LTD.**, Tokyo (JP)

(72) Inventor: **Hideki Endo**, Tokyo (JP)

(73) Assignee: **ALPS ALPINE CO., LTD.**, Tokyo (JP)

(**) Term: **15 Years**

(21) Appl. No.: **29/879,318**

(22) Filed: **Jul. 6, 2023**

(30) **Foreign Application Priority Data**

Feb. 15, 2023 (JP) ..... 2023-002807 D

(51) **LOC (14) Cl.** **14-01**

(52) **U.S. Cl.**

USPC **D14/204**

(58) **Field of Classification Search**

(57) **CLAIM**

The ornamental design for a speaker, as shown and described.

DESCRIPTION

FIG. 1 is a perspective view of a speaker, showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown are included for the purpose of illustrating portions of the speaker that form no part of the claimed design.

1 Claim, 7 Drawing Sheets
